ATTORNEYS.

UNITED STATES PATENT OFFICE.

THOMAS DIGNEY, OF BRIDGEPORT, CONNECTICUT.

CIGAR-ASH HOLDER.

Application filed July 30, 1921. Serial No. 488,505.

To all whom it may concern:

Be it known that THOMAS DIGNEY, a citizen of the United States, and resident of Bridgeport, in the county of Fairfield and State of Connecticut, has invented certain new and useful Improvements in Cigar-Ash Holders, of which the following is a specification.

This invention relates to improvements in 10 cigar ash retainers adapted to be supported from a cigar or holder and to enclose the cigar mounted therein.

The object of the invention is to provide a receptacle for the above purpose 15 which is especially desirable for enclosing a lighted cigar for smoking in open moving vehicles such as automobiles and in a way to prevent the dropping of ashes or blowing about of sparks, making it further 20 particularly applicable for use in windy weather or in places where it would be objectionable for ashes to be dropped.

A further feature of the invention is to provide a two-part receptacle of the above 25 class, each being made of a piece of wire gauze and one adapted to telescopically receive and support the other, so that the same may be readily adjusted for new 30 cigars of different lengths or parts of burnt cigars. Also to provide a closed forward 35 end portion which serves to shield the lighted end of the cigar, preventing the wind from blowing directly against it and thereby avoiding the rapid burning of the same when headed against the wind.

Further to provide means whereby the retainer can be detachably connected to the 40 cigar holder and thus be readily removed for the removal of the ashes or the insertion of a new cigar.

With these and other objects in view the invention resides and consists in the construction and novel combination and arrangement of parts hereinafter more fully 45 described, illustrated in the accompanying drawings, and pointed out in the claims hereto appended, it being understood that various changes in the form, proportion, size and minor details of construction with- 50 in the scope of the claims may be resorted to without departure from the spirit or sacrificing any of the advantages of the in- vention.

Similar characters of reference denote 55 like or corresponding parts throughout the several figures of the accompanying draw-

ings forming a part of this specification, and upon which,

Fig. 1 shows a perspective view of a cigar holder having my improved ash retainer 60 mounted thereon and positioned as in use;

Fig. 2 shows a central vertical longitudinal section of the holder, the retainer mounted thereon and cigar mounted within the holder and retainer; and

Figs. 3 and 4 show modified forms of construction, the same including a substitute for the cigar holder including a suitable means for supporting the retainer.

Referring in detail to the characters of 70 reference marked upon the drawings, 6 represents a cigar holder which for the most part is of the usual shape and construction, including a body portion having a central longitudinal hole 7 therethrough, a rib 8 75 around the smaller end, and a socket 9 in the opposite end to receive the small end of the cigar.

This particular cigar holder is provided with a ferrule 10 upon the periphery of 80 which is formed a pin-like projection 11 that serves for the attachment of the ash retainer to the holder.

The ash retainer proper comprises two cylindrical wire mesh sections 12 and 13, the 85 one adapted to slidably fit into the other, the member 12 being provided with an external annular rib 14 and the outer section 13 having a similar internal annular rib 15, each serving as a bearing against which 90 the adjoining section slidably operates and the two ribs in turn serving to form a stop against which each other strike when the sections have been fully extended. The inner end portion 16 of the smaller section 12 is preferably formed of solid metal and includes a bayonet-slot 17 which co-acts 95 with the pin 11 before mentioned for the securing of the smaller section of the retainer to the holder. The outer and larger section 13 of the retainer is likewise formed of wire gauze except its forward end 18, which as will be noted is made of solid sheet metal and serves to effectively close said end and form a shield for the lighted end 100 of the cigar when traveling against the wind thereby insuring an even burning of the cigar.

In the modification shown in Figs. 3 and 4 I have provided a sheet metal cylindrical 110 form of holder 6' having longitudinal slots 19 therein to afford a more ready attach-

ment to a cigar when shoved on the tapered end of the cigar 20. This obviously leaves the tip end of the cigar bare so that the smoker may directly engage the bare tobacco end of the cigar as preferred by a great many smokers. The sheet metal band 21 is slidably mounted upon the member 6' and serves to engage the end 16 of the section 12 between the holder 6' and the band 21 when the latter is shoved over the annular edge 16 as suggested by Fig. 4.

I am aware that it is not broadly new to provide a perforated ash retainer for enclosing lighted cigars, but so far as I am aware those which have been previously designed are of different construction from that herein shown and does not possess the novel features herein explained and later to be more specifically set up in the claims.

Having thus described my invention, what I claim and desire to secure by Letters Patent is—

1. A cigar ash retainer comprising a cy-

lindrical protector adapted to surround a cigar longitudinally, a removable cap at the outer end of said protector, a ring upon the inner end of said protector and at its outer side, and a tapered tube slidably engaged in said ring and at the inner side of the protector and adapted to engage over the end of a cigar disposed within the tube with the mouth engaging end of the cigar projecting outwardly from said tapered tube.

2. The invention as in claim 1, further characterized by longitudinal slots in the diverging end of said tapered tube adapted to render the same yieldable.

Signed at Bridgeport, in the county of Fairfield and State of Connecticut, this 28th day of July, A. D., 1921.

THOMAS DIGNEY.
